WASHOUT SUB FOR WELL PACKERS

Louis J. Birdwell, Oklahoma City, Okla., assignor to American Iron and Machine Works Company, Oklahoma City, Okla., a corporation of Delaware

Application July 16, 1949, Serial No. 105,154

4 Claims. (Cl. 137—68)

1

The invention pertains to oil well production tubing strings wherein a wall packer is used to close the annular space lying between the tubing string and the surrounding well casing.

The primary object of the device is to provide a short tubing section or "sub" which may be installed directly above the well packer, so as to form a continuation of the string, such section containing lateral fluid ejecting perforations for washing above the packer, and also containing means for selectively opening and closing such perforations.

A further object is to provide a device of this class which is positive in action, simple in operation, and comparatively cheap to manufacture.

Another object is to provide a device which may be used repeatedly.

Other objects will be apparent from the following description when taken in conjunction with the accompanying single sheet of drawings, wherein:

Figure 1 is an elevational view, partially in vertical section, showing the device in open or "un-set" condition; and,

Figure 2 is a similar view showing the device in closed or "set" condition.

Like characters of reference designate like parts in those figures of the drawings in which they occur.

In the drawings:

The reference numeral 1 indicates, as a whole, a tubular upper head having an axial bore 2 and an exteriorly threaded pin 3 whereby it may be attached to the lower end of a tubing or pipe string, not shown.

The pin 3 has an integral depending tubular sleeve portion 4 having therearound an exterior upwardly facing annular shoulder 5. The lowermost portion of the sleeve 4 is formed to produce a downwardly tapered portion or lip 6 which terminates in an annular end 7.

The device further includes: a metal ring 8 which surrounds the sleeve 4 above the shoulder 5, a tubular body 9 which is welded as indicated at 10, to the lower end of the ring 8, the lower end of the body being provided with internal threads 11; a lower head 12 which is tubular, and which terminates in a threaded pin 13 by which it may be connected to the upper end of a packer mandrel 14.

The upper end of the head 12 is threaded into the threads 11 of the sleeve 9, and is also provided with internal threads 15 for engaging the lower end of an upwardly projecting guide-sleeve 16. The guide-sleeve 16 extends upwardly within

2

the sleeve portion 4 of the head 1, and has a sliding working fit therein.

The body 9 is provided with a plurality of through ports or perforations 17, and the guide-sleeve 16 is provided with a similar plurality of radially spaced through perforations 18.

Nesting snugly between the inner surface of the body 9 and the outer surface of the guide-sleeve 16, there is provided an annular resilient sealing element 19 which seats upon the upper end 20 of the lower head 12. A metal split follower ring 31 is provided upon the upper end of the sealing element 19.

The inner surface of the sealing element 19 is flared upwardly to coincide with the taper of the portion or skirt 6 of the head portion 4.

The arrangement is such that when the head 1 is moved downwardly within the body 9, the tapered portion 6 enters the sealing element 19 and presses it outwardly into positive sealing engagement with the inner surface of the body 9. When the head 1 is at the lower end of its travel, the sleeve portion 4 thereof resides between the perforations 17 and 18 and acts to effectually close communication therebetween.

When the head 1 is at the upper end of its travel, the lower end 7 of the sleeve portion 6 lies above the perforations 17 and 18.

In order to normally hold the head 1 at the upper end of its travel, the wall of the body 9 is perforated, and the wall of the sleeve portion 4 is bored transversely about half way through in a plurality of places, and shear pins 21 are driven therein to anchor the two elements against relative vertical movements.

When it is desired to set the well packer in a cased well, the device and the packer are assembled in the condition illustrated in Fig. 1, and are lowered into the well on a string of drill-pipe or tubing, not shown. During the lowering operation, communication between the perforations 17 and 18 is open. In setting the packer, it is necessary that the packer expanding mandrel 14 be urged violently downward. When this is done, the shear-pins 21 are sheared, and the tapered portion 6 of the head 1 is lowered into expanding contact with the sealing element 19. Communication between perforations 18 and 17 is therefore effectually closed during the time the packer remains set in the well.

When it becomes desirable to remove the packer from the well, the first lifting movement of the tubing string will lift the tapered portion 6 out of the sealing element 19, and will raise the sleeve portion 4 from between the perforations 17 and

18, thus opening communication between the two perforations.

Should it then be found that the packer is stuck, due to a deposit of residue thereabove, wash-out circulation may be accomplished by forcing fluid downwardly through the pipe string to the bore 2, from whence it will be ejected into the well casing through the perforations 18 and 17 so that the deposit may be washed away.

The pins 21 must be replaced before the tool 10 is again run into the well casing.

Obviously the invention is susceptible to some change or alteration without defeating its practicability, and I therefore do not wish to be confined to the preferred embodiment shown in the drawings and described herein, further that I am limited by the scope of the appended claims.

I claim:

1. A washout device for installation in a tubing string at a point directly above a well packer, having in combination: a tubular upper head having its upper end adapted for attachment to the lower end of a section of production tubing to form a continuation thereof; two concentric bodies telescopically contacting the lower portion of the upper head, both exteriorly and interiorly, and slideable vertically with relation thereto; normally open outlet ports in the walls of said bodies for exhausting a washing fluid from the innermost body, said ports adapted to be closed by downward movement of the upper head; means for limiting vertical movement of the bodies; a lower tubular head carried by the lower ends of said bodies and adapted for attachment to the upper end of a packer; and a resilient annular sealing element supported by the lower head between the lower ends of the tubular bodies for sealing with the lower end of the upper head, when it is at the lower end of its travel.

2. A washout device for installation in a tub- 40

ing string at a point directly above a well packer, having in combination: an upper tubular head adapted at its upper end for attachment to the lower end of a section of production tubing to form a continuation thereof; a first tubular body telescopically surrounding the head and slideable vertically with relation thereto; a second tubular body slidably fitted within the head in concentric relation to the first body; interengaging means carried by the head and one of the bodies for limiting downward movement of the head; a lower tubular head carried by the lower ends of said bodies, and adapted at its lower end to connect the upper end of a well packer; communicating lateral ports in the two bodies for exhausting a washing fluid from the innermost body; an upwardly flared tubular packing element of resilient material mounted on the lower head, and lying in the annulus between the two bodies and the sleeve; and a downwardly tapered portion on the lower end of the upper head for entering and expanding the packing.

3. Structure as specified in claim 1, and shear means for normally holding the upper head at the upper end of its travel.

4. Structure as specified in claim 2, and shear means for normally holding the upper head at the upper end of its travel.

LOUIS J. BIRDWELL.
